IMPROVED METHOD OF HOLDING AND ADJUSTING SCAFFOLDS.

WILLIAM A. DEVON, OF PORT RICHMOND, NEW YORK.

Letters Patent No. 59,824, dated November 20, 1866.

SPECIFICATION.

TO ALL WHOM IT MAY CONCERN:

Be it known that I, WILLIAM A. DEVON, of Port Richmond, in the county of Richmond, and State of New York, have invented a certain new and useful improvement in securing and raising and lowering painter's and other Platforms or Scaffolds, of which the following is a full, clear, and exact description, reference being had to the accompanying drawing forming part of this specification, and in which—

Figure 1 represents a front view of a house in part with a platform or scaffold, having my improvement attached, applied thereto, and

Figure 2 a side or end view of the same, in section.

Like letters indicate corresponding parts in both figures.

Though equally applicable to other purposes where the securing and raising or lowering of a platform or scaffold is concerned, it will suffice here to describe my improvement as applied to a painter's scaffold for outside house-work. To avoid the risks and dangers incidental to temporary scaffolding of a fixed character, as well as to afford greater convenience to the workman in altering his position, so as to work at different elevations, tackle has been used secured to some fixed point above and to the platform below, with its rope or fall descending to the latter, such tackle being duplicated and applied to the two ends of the platform and arranged to work separately and independently of each other, though designed to be worked in unison by the workmen, one at either end of the platform, pulling on or slackening out the falls. This is a very inconvenient and insecure way of working; firstly, because it involves the necessity of a workman at each end of the scaffold, where one, except for working the falls, might suffice; and next, it is insecure, not only because there is the lashing or making tight of two ropes after the platform has been adjusted to its required elevation, but on account of the difficulty which exists in keeping the platform level whilst raising or lowering, by reason of the workmen at either end having to work in exact unison to avoid tilting of either end, even supposing the weight on the platform to be equally distributed, which is not always the case. My improvement obviates these difficulties, risks, and objections, and economizes labor by, if desired, enabling one man to adjust the scaffold. The nature of my invention consists, firstly, in passing the falls of the two end tackles which carry the platform over an intermediate sheave or pulley, or sheaves or pulleys, and attaching them below to the barrel of an ordinary windlass or winch, or its equivalent, and so that by turning said barrel both falls are of necessity equally drawn upon, or let out, and both simultaneously locked by putting into gear a stopper to the barrel; and my invention further consists in a combination with the platform of a windlass or winch on the latter, for operating the falls of the two end tackles, centre sheave or block working in contact with said tackles, and window-hooking frames to which the latter are hitched, and which, besides facilitating removal and attachment of the whole contrivance, may also serve as supports for a second or upper and stationary platform.

Referring to the accompanying drawing, A represents the front or other wall of a house or store in part, and B B its windows. C is the scaffold or platform which it is required to secure or adjust to any desired elevation, against the wall A. Projecting out from the windows B B, and resting on the sills thereof, are window-hooking frames D D, preferably of a gibbet form, with their horizontal legs resting on the sills, their vertical backs on the inside of the walls, and their angular front legs made to bear at their base against the front of the wall. The horizontal legs of these frames may be slid through the vertical backs thereof and be secured thereto by a pin passing through the back and any one of a series of holes in the horizontal leg to adjust the frame to grip different thicknesses of wall or window sills; or such adjustment may be effected by screw or otherwise. E E are the two end tackles secured at their tops to the window-hooking frames D D, and at their bottoms to the ends of the platform C, it may be by lifters, a a. F is an intermediate or centre block containing sheaves, and which may be hitched to a rod, b, connecting the frames D D, or which may be differently held, as, for instance, where there are three windows in line and the platform is a long one, by a third frame, D, arranged to project from the centre window. The falls, c c, of the end tackles E E, are rove through the block, F, and passed down and made fast to a winch barrel, G, by turning the handle, d, of which the platform is raised or lowered by the man on the platform accordingly as the falls are wound on or unwound from the barrel. When the platform has been sufficiently elevated or depressed, it may be held at its adjustment by any suitable stop to the barrel, say by throwing a catch or pawl, s, into lock with a ratchet wheel, e, on the end of the barrel. The winch may or may not be provided with gear to increase either its power or speed, according to the weight of the lift.

From this description it will be seen that both end tackles must pull or let out alike, consequently there can be no tilting of the platform. A single man may, if desired, do all the work of adjusting the platform, and the latter be locked at the position it is set, in a quick, simple, and efficient manner.

Though the several blocks may be otherwise held or supported, I prefer to use window-hooking frames as represented, which of course are dispensed with for hold-fasts of a different character or construction where there are no windows, as such frames establish a good grip and form convenient means for attaching and detaching the apparatus; also the same may be used by throwing planks across their tops as supports of or to a second or upper and stationary platform, as sometimes required.

What I claim as new and useful herein, and desire to secure by Letters Patent, is—
The combination, with the platform C, of the winch barrel G; falls *c c*, of end tackles E E; intermediate block F, and window-hooking frames G G, for operation together, essentially as herein set forth.

WM. A. DEVON.
